UNITED STATES PATENT OFFICE.

ALFRED C. REX, OF PHILADELPHIA, PENNSYLVANIA.

HATCHET.

SPECIFICATION forming part of Letters Patent No. 297,716, dated April 29, 1884.

Application filed February 1, 1884. (No model.)

To all whom it may concern:

Be it known that I, ALFRED C. REX, of the city of Philadelphia, county of Philadelphia, and State of Pennsylvania, have invented an improvement in Hatchets, of which the following is a specification.

My invention has reference to hatchets; and it consists in certain constructions whereby a steel blade may be cast in and firmly secured to the cast-iron body, and in a method of securing the handle to said body, all of which is fully set forth in the following specification, and shown in the accompanying drawings, which form part thereof.

The object of my invention is to construct a cheap hatchet for domestic purposes, which shall have all the qualities of the best steel hatchets.

In the drawings, Figure 1 is a sectional elevation of my improved hatchet, taken on line *x x*. Fig. 2 is a sectional plan of same, taken on line *y y*; and Fig. 3 is a cross-section of same, taken on line *z z*.

A is the steel blade, which is provided with a dovetail piece or extension, *B*, with a hole or aperture, *C*, formed therein, and also a slot or notch, *D*, upon one of its edges, for withdrawing nails. This blade is secured firmly to the body *E* by the latter being cast solid upon the said blade, as shown. The metal flows around the dovetail *B*, through the aperture *C*, and around the edges and sides of

the blade, as at *e*. By this means the said steel blade is firmly held, and could not possibly become loosened by use, and the gradual taper of the body to the blade is such that it is not readily perceived where the body ends and blade begins.

F is the hammer or head of the body, and *G* is the usual aperture, through which the handle *I* is passed and secured therein by the expanding wedge *I'*. As in small hatchets of this class it is generally found that the blade-handles become loose, I provide knife edges or points *H* on the face of the hole *G*, about half-way through, so that the wedge *I'* is driven in the wood of the handle, and is forced against the said projections, and they are buried into it, as shown in Fig. 3, thereby preventing any possibility of the handle working loose.

Having now described my invention, what I claim as new, and desire to secure by Letters Patent, is—

A hatchet the body of which is made of cast iron, and cast upon a steel blade formed with a dovetail extension, and an aperture through which the metal of the body flows, substantially as and for the purpose specified.

In testimony of which invention I hereunto set my hand.

ALFRED C. REX.
